COMBINATION BOX AND POCKET FOR
HANDBAGS

Frank Deak, New York, N. Y.

Application March 6, 1940, Serial No. 322,527

5 Claims. (Cl. 150—35)

This invention relates to hand bags, and has for its main object to provide a hand bag of novel construction and arrangement, whereby it may serve its purposes more efficiently than the hand bags now in use.

Another object of this invention is to provide in a lady's hand bag, various boxes and pockets, all arranged in an easily accessible system adjacent to the upper opening of the hand bag to make them easily accessible, each pocket or box having a specific purpose and being pre-prepared for the same.

Still further objects of this invention will be apparent as the specification of the same proceeds, and among others I may mention: to provide a hand bag as characterized hereinbefore, in which the various parts will be secured into the hand bag in a novel, simple and efficient manner; which will be comparatively simple in construction, easy and inexpensive to manufacture, and still will be adapted to attain the various objects mentioned hereinbefore, and also others, as will be apparent as this specification proceeds, and in which the major portion of the space in the hand bag will be clear for any use it may be desired to be put to, while my various novel containers and pockets will be all crowded at the two sides of the upper open end of the hand bag, out of the way and still easily accessible.

In the drawings:

Fig. 1 is a side elevation of a hand bag constructed according to my invention;

Fig. 2 is an end elevation thereof in a closed position, and

Fig. 3 is an end elevation in an open position;

Fig. 4 is a top view of the hand bag in an open position;

Fig. 5 is a separate view on an enlarged scale of one of the combination boxes to be used at the one side of my novel hand bag, the same being shown in an open position;

Fig. 6 is a similar view of another combination box to be used at the opposite side of my hand bag;

Fig. 7 is a fragmentary view of the upper end of my novel hand bag in an open position showing a pocket arranged at the top thereof, instead of the combination box indicated in Fig. 6;

Fig. 8 is a perspective view of a folded strip used in the securing of the pockets in my novel hand bag;

Figs. 8a and 8b are sectional details, the sections being taken on the lines 8a and 8b in Fig. 7;

Fig. 9 is a sectional elevation on the line 9—9 of Fig. 7, and on a larger scale, and

Fig. 10 is also a fragmentary sectional elevation on the line 10 in Fig. 7 and on an enlarged scale;

Fig. 11 is a fragmentary view of the upper part of my novel hand bag in an open position showing said first mentioned box and a pocket attached thereto, while

Fig. 12 is a sectional elevation on the line 12—12 of Fig. 11 on an enlarged scale.

Fig. 13 is a fragmentary section on the line 13—13 of Fig. 12.

Referring now to the drawings more in detail by characters of reference, the numeral 20 indicates my novel hand bag in general having the outer bag or container proper 21 of any appropriate construction and a hinged frame 22 to form its opening, as it is well known in this art, said frame having a right hand half 23 and a left hand half 24, joined by a hinge or pivot 25.

The usual carrying means 26 may be secured to the upper end of the frame 22 which may have any of the usual releasable securing means, as indicated at 27.

In the embodiment of my novel hand bag indicated in Fig. 4, a combination box, generally indicated by the numeral 28, may be secured to the left hand frame 24, and another combination box, generally indicated by the numeral 29, may be secured to the right hand frame 23, both in the manner and for the purpose to be explained presently.

The combination box 28 may have a bottom 30, upstanding side walls 31, a right hand cover 32, hinged on the respective portion of the side wall 31, as indicated at 33, and a left hand cover 34 hinged, as indicated at 35, each of said covers 33 and 34 normally being open, being urged into an open position by any appropriate means well known in this art, as by springs incorporated in the pivots 33, and 35, respectively.

The side wall of the combination box 28 is curved at its two upper corners, as indicated at 36, to better fit into the similar curve in the frame member 24, and two ring ears 37 are secured on the upper straight portion 38 of said side wall (Figs. 5 and 12).

Two hinge devices 39 are secured on the frame 24 (Figs. 4, 11 and 12), the lower plates 39a of which may have appropriate holes through which the perforated ears 37 of the box 28 may pass, as will be understood, and a pin 40 may be passed through the apertures of the ears 37 over the plates 39a, whereby the box 28 will be se-

cured within the frame member 24, adjacent to the left hand upper side wall 41 of the bag.

In the preferred embodiment of my device, I employ a second wall or piece of material 42 inside of said wall 41, said second inside sheet of material 42 terminating as at 43 and carrying two snap fastener buttons 44, into which may snap the depending snap fastener female members 45 at the inner lower side of the box 28, whereby said inner lower end of the box will be secured to said piece of material 42.

In the preferred embodiment of my device, I secure said second combination box 29 opposite to said box 28 in the right hand frame member 23 and in an entirely similar manner to that described for the box 28. Box 29 is similarly constructed to box 30 and has the hinged spring urged normally open covers 46 and 47.

Box 28 will have two cross or transverse walls 48 and 49 forming a larger central compartment 50, the bottom of which is covered by a mirror 51, secured in its place by any appropriate means, as by the spikes 52 struck out of the materials of the transverse walls 48 and 49 and bent over said mirror 51.

At the right hand compartment 53 a central depressed circular pocket 54 is formed, as it is well known in this art for a powder box, while a longitudinal short wall 55 will divide the left hand end of the combination box into a larger compartment 56 and a smaller compartment 57. A smaller circular pocket or depression 58 is formed in the compartment 56, as it is also well known in this art to receive the usual rouge or compact and a lipstick 59 may be placed in the compartment 57.

As has been mentioned hereinbefore, covers 32 and 34 are urged by springs in their hinges 33 and 35 into an open position, but, normally, said covers will be closed on the box, as indicated in Fig. 11, and kept in such a position by an appropriate spring catch 60 of any well known construction operable by a button or bar 61, the inward pressing of which will release the covers 32 and 34, while a simple pressing down of said covers will again engage the spring catch 60. Details of this construction are not further described, since they are well known in this art.

The construction of the box 29 is entirely similar to that of box 28 with the exception that box 29 has two transverse walls 62 and 63, the same forming a larger right hand compartment 64 covered by a spring operated arm 65 and used for the cigarettes 66, as will be understood.

A middle smaller compartment 67 in the box 29 may be used for a lighter, while the smaller left hand compartment 68 may be used for perfume.

The depending inside linings or pieces of material 42 may be left free, or it may be secured to the upper portions of the side walls 41 of the bag, but, in either case, the combination boxes 28 and 29 will have the tendency to nest in the frame members 23 and 24 adjacent to the upper opening of the hand bag and still close to the side walls thereof so that upon an opening of the hand bag, easy access will be had to the space therein, and all the necessary devices usually carried in a lady's hand bag will be easily and readily accessible in their respective compartments, as will be understood.

It is also to be noted that with this construction, any box may be easily removed when desired, exchanged or replaced by another device and still during the openings and closings of

the hand bag, the boxes will follow the movements of the upper portions of the side walls of the hand bag and will yield to it but will keep close to said side walls. For this latter purpose, the inner walls 42 may be additionally secured in an appropriate manner to the side walls 41.

It is also to be understood that in the drawings, the rest of the construction of the hand bag is not shown and it may have, and usually does have, additional linings between the side walls 41 and the inner sheets of material 42.

It is also to be noted that in the figures I show a novel specific design even for the hand bag, as best shown in Figs. 1 to 3, which will be attractive, adapted to the purposes of this invention, and which will have ample space available within the hand bag, particularly if the circumferential side walls 69 are made of more or less stiff rigid material.

The outwardly flaring central portion 70 of the bag will aid in the opening of the upper portion 41 and will make both, the combination boxes as well as the inner space in the hand bag, easily accessible, as best indicated in Fig. 3.

In addition to said boxes, or to replace one of them, I may employ specifically constructed pockets in my novel hand bag. These pockets are best illustrated in Figs. 7 to 10, and an appropriate bag or pocket 71 is formed of any usual textile or other material having the seams 72 around its circumference and a central seam 73 to divide it into two halves. The pocket may be made entirely closed, but the left hand half 74 thereof may have an opening or slit 75 by which access may be had into said half of the pocket, while the right hand half 76 may also have a similar slit or opening, which, however, normally is closed as by a so-called Zipper closing means 77.

I contemplate to provide the Zipper closed right hand compartment 76 for money and the open left hand compartment 74 for a handkerchief or the like.

In Figs. 7 to 10 I show this pocket secured in place of the box 29 which has been omitted in this embodiment of the hand bag. Many women do not smoke and do not use perfume, and in such cases the combination box 29 is not necessary. In this case, said box will be removed, as will be obvious and the pocket 71 will be secured to the lower plates 39a of the respective hinges 39.

The securing means of the pockets may include a folded doubled strip 78 of more or less rigid stiff material, like metal into the fold 79 of which the upper end 80 of the bag or pocket 71 may be placed and then spikes or sharp projections 82 thrust through and bent over the material of the pocket. The doubled strip 78 may have rearwardly projecting perforated ears 83 which may pass through the perforations of the respective hinge plates 39a, and a pin 84 will hold them in place, as will be understood, and similarly to the securing of the boxes 28 and 29 to said hinges 39. The pocket 71 may also depend free or it may be secured to the inner piece of material 42, or to the lining 41, in case said piece of material 42 is omitted, or to the lining together or over said piece of material 42.

It is also understood that the snap fastener elements 44 may be omitted from the piece of material 42 even if the same is left in the construction of the bag underneath the pocket 71.

In the normal and preferred form of my de-

vice, however, I have both boxes 28 and 29, and still I add to the construction thereof the same pocket 71 which was described hereinbefore as replacing the box 29.

For this purpose, the box 28 may have depending perforated plates 85 through which the upper perforated ears 83 of the pocket carrying folded strip of material 78 may be passed similarly as described hereinbefore with relation to the perforated lower plates 39a of the hinges 39, so that said pocket may be secured to the lower inner side of the box 28 in an entirely similar manner, as it has been secured to the hinges 39 as illustrated in Figs. 7 to 10, and used in a similar manner. This combination 10 of boxes and pockets is best illustrated in Fig. 4, and the details thereof further shown in Figs. 11 and 12.

In Fig. 8a, I show a section of the top part of the pocket, while in Fig. 8b, a similar section 20 at a place where a spike 82 is thrust through its material.

It will be understood that changes and variations may be made in the details and arrangements of my construction and in the combinations thereof, and I reserve my rights to all such changes and variations which are within the spirit of this specification and the scope of the claims hereunto appended.

What I claim as new, is:

1. In a lady's handbag, having an opening, and pivoted U frames encircling said opening, their pivoted motion opening or closing the handbag, a box pivotedly secured on one of the frames along the inside of the upper wall of the bag, 35 said frames being U shaped in cross section, said pivot being formed of two hinged plates, the upper plate being secured inside of the inner branch of the U of the frame, the lower plate being secured on top of the box, said top being adapted to be placed transversely across said U frame, the box resting alongside said wall but being adapted to be swung inwardly on said pivot when the handbag is open to make the box better accessible.

2. In a handbag having an opening and pivoted frames around the opening to open or close the bag, a pocket bag of flexible material, a substantially stiff strip of material along the top of said pocket bag, a hinge device secured on the inside of one of the frames, said hinge device being formed of two plates, the upper one of said plates being secured to said frame and the lower one having perforations, perforated ears on said strip of material adapted to be pushed through said perforations in the lower plate, and a pin adapted to be passed through the holes in said ears, thereby hingedly and releasably securing said flexible pocket bag on said

frame along the inside of the wall of the bag.

3. In a handbag having an opening and pivoted frames therearound, the pivoted motion of said frames opening or closing said handbag, pivot devices secured on said frames, each device being formed of two plates, the upper ones of said plates being secured on said frames and the lower ones having perforations, boxes having perforated ears on their tops, flexible pocket bags each having a substantially stiff strip of material secured along its top, and perforated ears on said strips of material, said ears on said boxes and on said pocket bags being adapted to be pushed through the perforations in respective lower hinged plates and a pin for each box and pocket bag adapted to pass through the holes in its ears, thereby to secure said boxes, and said pocket bags inside of said frames in a hinged removable and exchangeable manner.

4. In a handbag having an opening and pivoted frames therearound, the pivoted motion of said frames opening or closing said handbag, pivot devices secured on said frames, each device being formed of two plates, the upper ones of said plates being secured on said frames, and the lower ones having perforations, boxes having perforated ears on their tops, flexible pocket bags, each having a substantially stiff strip of material secured along its top, and perforated ears on said strips of material, said ears on said boxes and on said pocket bags being adapted to be pushed through the perforations in respective lower hinged plates, and a pin for each box and pocket bag adapted to pass through the holes in its ears, thereby to secure said boxes and said pocket bags inside of said frames in a hinged releasable and exchangeable manner, depending perforated plates at the lower end of the boxes, said ears on the pocket bags being adapted to pass through the holes in the depending plates, and pins to pass through the holes and ears, to releasably and exchangeably secure said pocket bags at the lower ends of said boxes when desired.

5. In a handbag having an opening and pivoted frames therearound, the pivoted motion of said frames opening or closing said handbag, a pivot device secured on one of said frames, said device being formed of two plates, the upper one of said plates being secured on said frame and the lower one having perforations, a box having perforated ears on its top, said ears on said box being adapted to be pushed through the perforations in the lower hinged plate, and a pin for said box adapted to pass through the holes in its ears, thereby to secure said box inside of said frame in a hinged removable and exchangeable manner.

FRANK DEAK.
